US0D1077689S

(12) **United States Design Patent** (10) **Patent No.:** **US D1,077,689 S**
(45) **Date of Patent:** **** Jun. 3, 2025**

(54) **STROLLER**

(71) Applicant: **Zhongshan Kanglaiya Trade Co., Ltd.**, Guangdong (CN)

(72) Inventor: **Zelian Jiang**, Guangdong (CN)

(73) Assignee: **Zhongshan Kanglaiya Trade Co., Ltd.**, Zhongshan (CN)

(**) Term: **15 Years**

(21) Appl. No.: **29/978,694**

(22) Filed: **Dec. 13, 2024**

(51) LOC (15) Cl. **12-12**

(52) U.S. Cl.

USPC **D12/129**

(58) **Field of Classification Search**

USPC D12/128, 129, 130, 131; D21/535

(57) **CLAIM**

The ornamental design for a stroller, as shown and described.

DESCRIPTION

FIG. 1 is a first perspective view of a stroller showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is an enlarged view of portion of FIG. 1.

The broken lines in the drawings depict portions of the stroller that form no part of the claimed design.

1 Claim, 9 Drawing Sheets
